UNITED STATES PATENT OFFICE

CHARLES T. BRADY, OF DETROIT, MICHIGAN

DESIGN FOR A LAMP SHADE

Application filed February 2, 1929. Serial No. 29,883. Term of patent 14 years.

To all whom it may concern:

Be it known that I, CHARLES T. BRADY, a citizen of the United States, residing at Detroit, in the county of Wayne, and State of Michigan, have invented a new, original, and ornamental Design for Lamp Shades, of which the following is a specification, reference being had to the accompanying drawing, forming part thereof.

The figure is a view in perspective, looking at the underside of the lamp shade showing my new design.

I claim:

The ornamental design for a lamp shade, as shown.

CHARLES T. BRADY.
